UNITED STATES PATENT OFFICE.

THOMAS A. BRIGGS, OF ARLINGTON, MASSACHUSETTS.

PRINTING-MACHINE.

SPECIFICATION forming part of Letters Patent No. 469,981, dated March 1, 1892.

Application filed February 15, 1890. Serial No. 340,507. (No model.)

To all whom it may concern.

Be it known that I, THOMAS A. BRIGGS, of Arlington, in the county of Middlesex and State of Massachusetts, have invented a certain new and useful Improvement in Web-Printing Machines, of which the following, taken in connection with the accompanying drawings, is a specification.

My present invention relates more especially to a machine having suitable devices for printing one or more characters upon a continuous strip of paper and to repeat the character or characters two or more times, if desired, at varying and adjustable distances with a regular consecutive order of ascending characters or numbers within the compass of the given machine and automatically to repeat indefinitely without additional adjustment.

In the annexed drawings, Figure 1 is a sectional elevation on the line 1 1 of Fig. 2. Fig. 2 is a plan view with the inking apparatus removed and with the upper parts of the standards broken away. Fig. 3 is a sectional view on line 2 2 of Fig. 4. Fig. 4 is a sectional elevation of a portion of the machine on the line 3 3 of Fig. 3. Fig. 5 is a view showing the surface of a printed bundle-slip, illustrating the work that may be done by the machine. Fig. 6 is a diagrammatic view illustrating the operation of the machine, and Fig. 7 is a side view of the inking devices for the printing-cylinders.

In Fig. 5 I have shown a common "bundle-check" as used in ordinary retail stores. These checks are formed in two or more parts, the sections to be torn off, as indicated. One part is sent to the cashier by the salesman with the money and another sent with the goods to the bundle-counter. Each salesman has a book corresponding to his number, which ordinarily contains fifty checks bound together. I have therefore illustrated the principles and devices of my present invention by a machine arranged to print or number up to fifty checks. The spirit of my invention, however, covers a greater or less combination. The number that any given machine will reach is simply a matter of construction upon mathematical calculation on the basis and arrangement of devices herein set forth.

Now referring to the drawings, Fig. 1, T

represents the frame, which supports the mechanism of my improved printing-machine, said frame being clamped or firmly secured 55 to rigid standards T' T', which extend above the frame and have secured to their upper ends the horizontal arms L, on which is mounted the horizontal shaft of the paper-roll K.

E and E' represent two rotary rubber-faced 60 cylindrical impression-cylinders extended horizontally across the machine and journaled in the sides of the frame T. Between the upper impression-cylinder E' and paper-roll K and parallel therewith is a guide-roller H', 65 and between the two impression-cylinders is a similar guide-roller H. The web of paper to be imprinted passes from the roll K to the roller H', which guides the paper to the upper impression-cylinder E', from whence it passes 70 over the outer side of the guide-roller H, and thence over the inner face of the lower impression-cylinder E and out from the machine.

In order to render the distance of travel of 75 the paper from impression-cylinder to impression-cylinder adjustable and thereby vary the distance between the impressions to be made on the paper in passing over the said impression-cylinders, as may be desired, I journal 80 the roller H at its ends to racks V, which are connected to the frame T, movable longitudinally toward and from the type-wheel, as shown in Fig. 1 of the drawings, and with said racks engage pinions R, secured to a 85 shaft journaled in the aforesaid frame and provided with suitable means for turning the shaft with its pinions. The rotation of the latter move the racks V longitudinally, and thus carry the roller H in or out between the 90 impression-cylinders, and thereby vary the length of the travel of the paper between the impression-cylinders, and consequently, also, vary the distance between the impressions to be made upon the paper, as represented by 95 the numerals "1 1" on check in Fig. 5 of the drawings.

A denotes the type-wheel, which is axially parallel with the impression-cylinders E E' and is secured to the shaft C, journaled in 100 suitable bearings in the frame T. The direction of rotation of the type-wheel is indicated by the arrows in Figs. 1, 3, and 6 of the drawings.

The type-wheel A consists of a circular plate A', formed with two concentric rims A² and A³, and through these rims extend radially a series of channels x⁵, as shown in Fig. 4 of the drawings.

x⁴ represents types, which are secured to holders x' in any suitable manner, as by dovetailing them in the outer faces of the holders, as represented in Fig. 3 of the drawings.

10 The type-holder has extending from its back a stem x, which is seated movably endwise in the channels x⁵ in the two wheel-rims A² and A³ and is retained therein by a spiral spring x³, surrounding the stem x and bearing with 15 its outer end on the inner face of the outer rim A³ and with its inner end on a pin or lug x², attached to the aforesaid stem, and thereby holding the type-holder in its normal or retracted position. Said pin or lug also serves 20 as a stop by resting on the inner rim A² of the wheel A. The same result, however, may also be attained by the head of the type-holder coming in contact with the exterior of the outer rim A³. Upon the inner side of the inner 25 rim A² of the wheel A is formed an internal gear a, having in this case one hundred teeth, as shown in Figs. 1 and 3 of the drawings, for the purpose hereinafter described.

On the hub C' of the wheel A is loosely 30 mounted an arm B, one end of which is bifurcated or formed with a longitudinal slot and receives through it a cross-bar Q, attached to the frame, and is thereby prevented from rotating with the wheel A. The opposite end 35 of said arm has smooth cylindrical eyes transversely through it at points between the gear a and axis of the wheel A and in radial lines extending from said axis to the axes of the impression-cylinders E E', said impression-cylinders thus facing the type-wheel directly 40 opposite the two pinions b b'. Through each of said eyes passes a stud-pin c, having a smooth cylindrical neck in the eye of the arm and formed with an eccentric c⁴ at the end adjacent to the wheel A and with a head c⁵ on the end of the eccentric. On the two eccentrics are journaled the pinions b b', which mesh with the gear a of the type-wheel A. The opposite end of the stud-pin projects from 45 the outer face of the arm B and is screw-threaded and provided with a set-nut c³, as shown in Fig. 4 of the drawings. Said nut bearing on the outer face of the arm and the head c⁵ engaging the inner face of the pinion completes the connection of the pinion to the arm. Another nut c² is fastened to the extremity of the stud-pin by means of a pin passing transversely through said parts. This latter nut serves as a knob by which to turn 55 the stud-pin, and thus change the axial position of the eccentric when desired.

To the inner faces of the pinions b b' are secured, respectively, lugs y y² by screws y³ or other suitable means. Said lugs are in 60 such positions as to cause them to engage the inner end faces of the stems x of the type-holders x' during the rotation of the type-

wheel, and thereby push the latter endwise outward, as shown at y² in Fig. 3 of the drawings. By the axial adjustment of the eccentric c⁴, as hereinbefore described, the pinion b is moved toward or from the gear a, and thus the lug b carried thereon is caused to push the type-holder to a greater or less degree outward, and thus a heavy or light impression of the type 75 upon the paper to be printed is obtained, as may be desired. When it is desired to print each character or numeral singly, one of the pinions can be moved toward the axis of the type-wheel A by turning the eccentric c⁴ sufficiently to prevent the lug y from actuating the type-holder x' without throwing the pinion completely out of engagement with the gear a.

The hub C' of the type-wheel A is split, as 85 shown in Figs. 1 and 4 of the drawings. Outside of the arm B and on the split hub C' is placed a split collar B³, which may be held in place by a set-screw b⁶. A screw y⁴ passes through ears on the split collar and pinches 90 the same upon the split hub C', and by this means the most perfect alignment of the wheel A upon its shaft C is obtained.

N represents a form-cylinder, which is parallel with and in contact with the periphery 95 of the impression-cylinder E', and has secured to its peripheral face stereotypes or electrotypes by which the usual headings are printed on the successive slips produced from the web of paper K in its passage through the 100 machine. Said cylinder is journaled in suitable bearings in the sides of the frame T.

G denotes the main driving-pulley of the machine. On the shaft G' of said pulley is rigidly mounted a gear-wheel M, which meshes 105 with a gear-wheel Z on the shaft of the printing-cylinder N. The gear Z engages a gear-wheel m on the shaft of the platen-cylinder E'. The periphery of the latter gear-wheel is indicated by dotted lines in Fig. 1 of the 110 drawings, and it engages a spur-wheel n, secured to the shaft C of the type-wheel A, as best seen in Fig. 2 of the drawings, and only indicated by dotted lines in Fig. 1 of the drawings. The shaft of the second impression-cylinder E has also a gear on its shaft, which gear meshes with the spur-wheel n, and thus 115 said latter impression-cylinder receives rotary motion.

The inking-rollers o⁴ and o⁵ receive rotary 120 motion by gears on the ends thereof engaging the gear-wheel Z on the shaft of the printing-cylinder N, as indicated by dotted lines in the rollers in Fig. 1 of the drawings. The inking-rolls, Fig. 1, (represented by o o' o² o³ 125 o⁴ o⁵), are made in the ordinary manner known to the art, and are arranged to receive ink from the ordinary fountain, (represented by P.) The two rolls o⁴ and o⁵ are both in contact with the roll o², the roll o⁴ carrying the 130 ink to the form-cylinder N, while the roll o⁵ carries ink to the type-wheel A. Said inking-rolls have the usual adjustability to allow for wear, &c. The inking-rolls may be turned

by frictional contact of their surfaces instead of gears, if preferred.

Any suitable power may be used and any variation in number or sizes of gears, inking-rolls, &c., can be made, as desired, if the relative correspondence of parts is maintained.

One form of mechanism for inking the form-cylinders is shown in Fig. 7 of the drawings, and consists of ratchet 1, fixed to the shaft, to which the roller o is also rigidly secured. On said shaft is loosely mounted an arm 2, the free end of which is connected with an eccentric 8 on shaft G' . The hub of said arm is formed with a cam 3. A pawl 4 is pivoted to the arm and engages the ratchet. The roller o' is pivoted to the upper ends of two vertical arms 5, pivoted to the frame. One of these arms is formed with a lever 6, the free end of which is held in contact with the cam 3 by means of a spring 7. The roller o^2 is rotated by contact with the rollers o^4 and o^5 . The eccentric 8 imparts an oscillatory motion to the arm 2, and by the alternate engagement and release of the ratchet 1 by the pawl 4 the roller o receives an intermittent rotary motion. During the oscillation of the arm 2 the cam 3 thereof intermittently depresses the lever 6 and thereby transmits oscillatory motion to the roller o' , which is thus brought alternately into contact with the rollers o and o^2 , and thereby carries the ink to the latter roller. The roller o^3 serves to spread the ink evenly on the roller o^2 , and the contact of the latter with the rollers o^4 and o^5 applies thereto the ink. It is necessary, however, for the best work that the type-wheel A and the impression-cylinders E E' should have the same velocity, otherwise the printing would be blurred. The paper is preferably used from a roll; but it may either be carried through the machine and cut off afterward, or the paper may be previously cut into suitable sizes and carried through by tapes or other devices. The paper may also be rewound after printing, if desired.

Having sufficiently described the operative parts of my present invention, I will now proceed to describe its mode of operation.

For convenience I have represented a machine in the drawings as carrying numeral-faced type for the purpose of numbering each check with the same number twice, and thence continue by a regular ascending series of numbers from one to fifty without stopping or making any adjustment in any way, the checks being formed and numbered upon a continuous strip of paper, as herein described.

By referring to Figs. 3 and 6 the operation will be understood.

The paper being adjusted and the distance between impressions properly regulated by the position of the roller H, as hereinbefore explained, and the ink and inking devices in proper order, the machinery is set in motion. The type-wheel A, being revolved by its shaft

C in the direction of the arrow, brings the types X^4 successively opposite the impression-cylinders E E'. When the type having the numeral "1" on its face arrives opposite the face of impression-cylinder E', the lug y^2 on the pinion b presses outward the type-holder x' and the figure or numeral "1" is impressed upon the paper or other material, (illustrated in S S', Fig. 5.) The type-wheel A, continuing to revolve and communicating motion to the pinion b , carries the lug y^2 out of contact with the type-holder (carrying "1") and allows the same to be returned to its normal position on the periphery of the wheel A by the force of the spring X^3 . The revolving type-wheel A carries the aforesaid type-holder to a position directly opposite the impression-cylinder E, and at the same time the pinion b' is turned to bring its lug y in contact with the type-holder, which is thereby again pushed out to make the impression of the type on the paper as it passes between said type-holder and impression-cylinder. Said second impression is made sufficiently distinct without a second application of ink to the type. In this manner each type is caused to make two impressions a predetermined distance apart on the paper, as represented in Fig. 5 of the drawings, the distance between the impressions being determined by the adjustment of the guide-roller H, interposed between the two impression-cylinders E E', as hereinbefore described. If the internal gear a of wheel A have one hundred teeth and the pinions b and b' have each thirty-four teeth, it is obvious that during one revolution of wheel A each of the pinions b and b' will revolve three times, lapping two teeth of gear a ; or, in other words, three revolutions of a pinion will mesh in one hundred and two teeth of the gear a , and the following numbers will have been printed upon the paper—viz., "1 1," "2 2," "3 3," "4 4."

In a machine arranged for fifty numbers, as illustrated in the drawings, there being one hundred teeth in gear a of wheel A, it will of course take two teeth for each number. Now the pinions b and b' having each thirty-four teeth, it follows that in each revolution of the wheel A there will be two teeth short of completing the third revolution of pinions b and b' . Starting with lug y^2 of pinion b pressing outward numeral "1," it will take thirty-four teeth of gear a to produce one revolution of pinion b , so that lug y^2 will press outward the type-holder carrying numeral "2," and sixty-eight teeth of said gear will cause the lug y^2 to push out the type-holder carrying numeral "3," and one hundred and two teeth will actuate in a similar manner the type-holder carrying numeral "4." Now one hundred and two teeth on gear a would carry past one type-holder, and consequently the lug y^2 would on the third revolution of the pinion strike over one type-holder each time, so that instead of again striking "1" it would strike "4" upon the third

- revolution of pinion b and the commencement of the second revolution of wheel A. It will be noticed that the first revolution of wheel A prints numerals "1 1," "2 2," "3 3;" the second revolution prints "4 4," "5 5," "6 6," and so on. This follows from the relative arrangement of the teeth in gear a of wheel A with teeth b^4 in pinions b and b' , and it is mathematically impossible that any error can occur.
- 5 If it were desired, the same principle could be applied to print a greater or less number of characters or numerals consecutively. For instance, by arranging for one hundred numbers each type would be operated by one tooth 10 of gear a and wheel A, and pinions b and b' would each be formed with thirty-three teeth, and in operation there would be a gradual falling off of one each time round instead of going one ahead, as in a fifty-number wheel. This 15 will be apparent by an examination of Fig. 6, in which the general principle is illustrated. I do not, therefore, confine myself to the precise combination shown nor the exact details of parts described, as many modifications of 20 the same principle can be made, as already suggested. For instance, the size of the wheels, rolls, and parts may be varied, the number may be increased or diminished, and the special arrangement of pinions b and b' could 25 be modified and work efficiently.
- The devices contained in my present invention may be employed in connection with a printing-machine either with or without inking devices. It will thus be seen, that I 30 am able, with a wheel arranged to carry type for any given number of numerals or other characters attached to the periphery of the wheel, to automatically print one or more impressions of every character successively 35 from lowest to highest on a continuous strip 40 of paper and to repeat them indefinitely without change or adjustment of any of its parts.
- Having now fully described my invention, what I claim, and desire to secure by Letters 45 Patent of the United States, is—
1. A printing-machine comprising a rotary type-wheel having type-holders seated radially movable in the periphery of said wheel and held normally retracted therein, and a 50 lug revolving about a stationary axis and adapted to push the type-holders successively outward to their printing position, as set forth.
2. The combination of a rotary type-wheel 55 provided with an annular internal gear and having type-holders seated radially movable in the periphery of said wheel and held normally retracted therein, a pinion journaled to an axis held stationary between the afore- 60 said internal gear and axis of the type-wheel and meshing with said gear, and a lug on said pinion engaging successively the type-holders during the rotation of the pinion, substantially as set forth.
- 65 3. In combination with the rotary type-wheel having type-holders seated radially

movable in the periphery thereof and normally retracted in the wheel, and a plurality of revolving lugs adapted to push the type-holders outward and sustained adjustably in 70 their position in relation to the type-holders to keep them out of contact therewith, as and for the purpose set forth.

4. The combination of the type-wheel provided with an annular internal gear and with 75 type-holders seated radially movable in the periphery of said wheel and normally retracted therein, eccentrics clamped adjustably to stationary supports, pinions mounted on said eccentrics and meshing with the aforesaid internal gear, and lugs attached to the pinions in position to push the type-holders successively outward during the rotations of the pinions, 80 substantially as described and shown.

5. The combination of a rotary type-wheel 85 having radially-movable type-holders normally retracted in the wheel, lugs revolving about stationary axes and adapted to push outward the aforesaid type-holders at different parts of the wheel, rotary cylindrical impression-cylinders respectively opposite the aforesaid lugs, and a paper-guiding roller between said impression-cylinders, as set forth.

6. The type-wheel A, provided with the perforated concentric rims A^2 A^3 and internal 95 gear a , the type-holders X' , having stems X , seated movably longitudinally in the perforations of said rims, springs X^3 , retracting the type-holders, the pinion b' , mounted on a stationary support and engaging the gear a , and 100 the lug y , attached to said pinion and engaging the inner ends of the type-holder stems, substantially as described and shown.

7. The combination, with the supporting frame, of a rotary type-wheel carrying a series of radially-movable type-holders distributed around the periphery of said wheel and provided with the internal gear a , springs holding the type-holders normally retracted in the wheel, the cross-bar Q, secured to the 110 frame, the arm B, mounted loosely on the shaft of the type-wheel and having one end confined on the aforesaid cross-bar, pinions b , b' , pivoted to the opposite end of said arm, lugs y^2 y , attached, respectively, to said pinions and adapted to push outward the type-holders, the spur-wheel n on the shaft of said 115 type-wheel, the impression-cylinders E E' , arranged with the centers of their axes in lines extending radially from the axis of the type-wheel through the axes of the aforesaid pinions, and gear-wheels on the shafts of said impression-cylinders meshing with the spur-wheel n , substantially as set forth.

8. The improved printing-machine consisting of the supporting-frame T, the type-wheel A, having radially-movable type-holders held normally retracted in the wheel, internal gear a on said wheel, pinions b b' , mounted on a stationary support and engaging the gear a , 120 lugs y^2 y on said pinions pushing the type-holders outward, rotary impression-cylinders 125

130

E E', facing the type-wheel directly opposite the aforesaid pinions, the form-cylinder N, facing the impression-cylinder E', the gear-wheel M, mounted on the driving-shaft, and 5 gears respectively on the aforesaid form-cylinder, impression-cylinders, and type-wheel receiving motion from the said gear-wheel M, substantially as set forth.

In testimony whereof I have signed my name to this specification, in the presence of 10 two subscribing witnesses, on this 11th day of February, A. D. 1890.

TIOS. A. BRIGGS.
